UNITED STATES PATENT OFFICE.

ANTON OHNEMUS, OF QUINCY, ILLINOIS.

DESIGN FOR A BOTTOM PLATE FOR STOVES.

SPECIFICATION forming part of Design No. 26,037, dated September 15, 1896.

Application filed March 24, 1896. Serial No. 584,696. Term of patent 7 years.

To all whom it may concern:

Be it known that I, ANTON OHNEMUS, a citizen of the United States, residing at Quincy, in the county of Adams, State of Illinois, have 5 invented and produced a new and original Design for a Bottom Plate for Stoves, of which the following is a specification, reference being had therein to the accompanying drawings.

10 Figure 1 is a plan of a bottom plate embodying the design, and Fig. 2 is a vertical longitudinal section through the same.

15 The leading feature of the design consists in a corrugated longitudinal plate having rounded ends and straight substantially parallel sides joining said ends and formed with alternate depressions and elevations, all emanating from a point at the longitudinal and transverse centers of the bottom plate.

20 F is the bottom plate, provided with the

corrugations throughout its surface, the outlines of which are formed by circles or arcs of circles, all emanating from a central point, which is at the junction of the longitudinal and transverse diameters of the plate, which is of greater length than width and provided with rounded ends and substantially straight sides joining the same, the corrugations and depressions all falling within the boundary-line of said plate. 25

30 What is claimed as new is—

The design for a bottom plate for a stove substantially as herein shown and described.

In testimony whereof I affix my signature in presence of two witnesses.

ANTON OHNEMUS.

Witnesses:

GEORGE R. SMITH,
WILFRED AMBURN.
